UNITED STATES PATENT OFFICE.

JOHN HARTLEN FOWLER, OF ORBISONIA, PENNSYLVANIA.

SAFETY-PIN.

1,241,948.

Specification of Letters Patent.

Patented Oct. 2, 1917.

Application filed May 19, 1916. Serial No. 98,600.

To all whom it may concern:

Be it known that I, JOHN H. FOWLER, a citizen of the United States, and a resident of Orbisonia, in the county of Huntingdon 5 and State of Pennsylvania, have made certain new and useful Improvements in Safety-Pins, of which the following is a specification.

My present invention relates generally to 10 safety pins, my object being to provide a safety pin of simple, inexpensive construction and having generally a greater capacity for connection of articles of clothing and the like than is provided by the ordinary safety 15 pin now in use.

More particularly my invention aims to provide a safety pin having means whereby additional grip upon articles of clothing and the like to be connected is attained beyond 20 that afforded by the ordinary safety pin or by any other pin whose connection with the clothing depends merely upon the passage of a prong or pin member therethrough.

In carrying out these objects I provide a 25 construction of safety pin to be hereinafter described with respect to the accompanying drawing and wherein—

Figure 1 is a plan view illustrating my improved pin with a flexibly attached keeper. 30 Fig. 2 is a vertical longitudinal section taken therethrough substantially on line 2—2 of Fig. 1.

Fig. 3 is a view similar to Fig. 2 illustrating a slightly modified form of keeper.

Fig. 4 is a plan view illustrating another 35 modified form of keeper.

Fig. 5 is a partial longitudinal section through the forms shown in Fig. 4 and taken substantially on line 5—5 of said figure, and

Fig. 6 is a detail perspective view illustrating the guard carrying member of the keeper shown in Figs. 4 and 5.

Referring now to these figures, my improved pin which is of the same construction 45 throughout the several figures essentially comprises a pair of spaced parallel prongs 10 bent at right angles from and with respect to the head 11, the said prongs being sharpened at their forward or outer ends 50 and having their rear or inner ends integral with the inwardly projecting rear side extensions 12 of the head 11, the latter of which has a forward cross bar 13 spaced forwardly from and generally parallel with the 55 extensions 12 and projecting transversely across and overlying the rear portions of the

prongs 10 so that, by virtue of the integral connection of the parts and their formation from a single section of wire as shown, the natural resiliency thereof tends to urge the 60 cross bar 13 toward and against the prongs 10, thus forming a clasp for engagement with the material through which the prongs are extended.

In this manner the maintenance of the 65 safety pin in place in use is primarily attained by the clasping action of the cross bar 13 upon one or the other of the connected parts, or possibly both of such parts, the usual severe strain upon the keeper being in 70 this manner relieved to a considerable extent.

In the present case the keeper may be of various forms, for instance, in the nature of a rectangular frame 14 as seen in Figs. 1 and 2 having forward intermediate and rear 75 cross bars 15, 16 and 17 respectively, it being noted that the frame so shaped is angular in form, with its intermediate cross bar 16 in a plane above a plane connecting the forward and rear cross bars 15 and 16 so as to frictionally grip the forward sharpened ends of the prongs 10 when projected therethrough in the manner shown in Fig. 2, the keeper so formed being attached to the cross bar 13 by means of a flexible elastic connection 18 in 80 order to prevent its displacement, and the forward cross bar 15 having an upturned flange 19 therealong forming a guard in advance of the pointed extremities of the 85 prongs 10.

As shown in Fig. 3 the keeper 20 is attached to the cross bar 13 by a flexible elastic connection 21 similar to the connection 18 before described, but is itself constructed differently, being formed for instance of 95 wire with its intermediate cross bar 22 in a plane above a plane connecting its forward and rear cross bars 23 and 24 so as to firmly engage the pointed ends of the prongs 10 in the manner previously described in connection with the forms shown in Figs. 1 and 2.

In accordance with the arrangement shown in Figs. 4, 5 and 6 the keeper consists of a U-shaped frame 25, the forward cross bar of which supports a pivoted guard 26, 105 and the rear extensions of which have their extremities bent around the cross bar 13 as seen at 27 to pivotally support the keeper in position, the guard 26 consisting of depending angularly disposed plates 28 and 29, the 110 forward of which is apertured to receive the pointed extremities of the prongs there-

through, and the latter of which has an intermediate upset portion 30 provided with a slit into which the pointed extremities of the prongs 10 are confined.

5 In either form, however, as before described the usual strain upon the keeper of a safety pin is obviated in accordance with the specific construction of the safety pin as provided by my invention and it is to be
10 understood for this reason that further modifications and changes may be made in the keeper or guard portion of the device at least, without avoiding the invention.

I claim:

15 A safety pin comprising a pair of spaced

parallel prongs and a head disposed at right angles to the prongs at the rear ends thereof, said head being in the form of a laterally elongated loop having rear inwardly projecting extensions integral with the rear 20 ends of the prongs and having a forward cross bar overlying the prongs adjacent the rear ends thereof, and a keeper having means to frictionally engage the free ends of the prongs, said keeper being flexibly connected to the said cross bar of the head. 25

JOHN HARTLEN FOWLER.
